UNITED STATES PATENT OFFICE.

ELIAS KISSINGER, OF GIRARDVILLE, PENNSYLVANIA.

RUBBER BOOT.

SPECIFICATION forming part of Letters Patent No. 501,082, dated July 11, 1893.

Application filed November 29, 1892. Serial No. 453,533. (No model.)

To all whom it may concern:

Be it known that I, ELIAS KISSINGER, a citizen of the United States, residing at Girardville, in the county of Schuylkill and State of Pennsylvania, have invented certain new and useful Improvements in Rubber Boots; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to rubber boots or shoes. It has for its object to provide a boot or shoe that will be simple of construction, durable in use and comparatively inexpensive of production.

With these objects in view, the invention consists in certain features of construction and combination of parts which will be hereinafter described and claimed.

In the accompanying drawings in which similar letters of reference denote corresponding parts: Figure 1 is a side elevation. Fig. 2 is a cross section on line $x-x$, Fig. 1. Fig. 3 is a longitudinal section. Fig. 4 is a view of the stiffener.

A denotes the boot leg, and a the vamp, and a' the insole, each of which is of the usual and well known construction. After these parts have been properly assembled, a short foxing, B, is folded under the insole and projects, with its upper edge, over the vamp and counter about an inch. The outsole, C, and heel, D, are then placed in position. The sole is of that style known as a "Scotch sole," and has an inclined portion b embracing the foxing.

In the manufacture of rubber boots heretofore, it has been the custom to roll the edge of a rubber sole up against the vamp. This is found objectionable for many reasons, among which may be noted the danger of cutting the vamp when the edge of the sole is brought into contact with a sharp stone or the edge of ice. By the foregoing described construction this objection is overcome.

Heretofore great difficulty has been experienced in the production of a rubber boot that will not split at the intersection of the instep with the leg and at the side seams. At these points there is a continual strain, and the

tendency is to split or crack the rubber. To overcome this, I secure to the central portion 55 of the vamp a stiffener, E, of any suitable material. This stiffener is composed of the body portion, e , the central wing, e' , which projects under the central portion of the instep, and the diverging wings, e^2 , which lie 60 back of the seam. Not only does this stiffener prevent the breaking of the rubber at the points to which it is secured, but at the same time serves to keep the boot in its proper shape. For the same purpose I provide a 6 stiffener H at the back of the boot. This stiffener has a line of perforations, f , in its upper edge, so that, when it is placed in position, the rubber being in a semi-plastic state, will be forced through the perforations and 70 thereby secure it in place. Heretofore, after the lining at the heel of a rubber boot has been worn away, the heel of the wearer has been brought into contact with a rubber surface which, being of a rather adhesive character, prevents the ready removal and insertion of the foot. To overcome this objection I secure to the stiffener a leather supplemental counter, G, which extends from seam to seam, and upwardly about three (3) inches. 75 This will furnish a smooth surface to the heel of the wearer and will enable him to easily insert or remove his foot from the boot without the liability of blistering it.

If desired, the outer sole of the boot may 85 be provided with a steel shank.

Having thus described my invention, I claim and desire to secure by Letters Patent of the United States—

As an improved article a rubber boot comprising the leg, the vamp, the outsole, the insole, the foxing, the stiffener E, secured to the vamp, consisting of the body portion, the central wing and the diverging wings, the leather counter, the stiffener H, located between the 90 counter and heel portion, projecting up above the counter and having a series of perforations therein through which portions of the rubber project, substantially as described.

In testimony whereof I affix my signature in 100 presence of two witnesses.

ELIAS KISSINGER.
